UNITED STATES PATENT OFFICE.

ARTHUR W. REED, OF BOSTON, MASSACHUSETTS, ASSIGNOR OF ONE-HALF TO WALTER B. TANNER, OF BOSTON, MASSACHUSETTS.

MOTOR-VEHICLE SURFACE SANDER.

Application filed September 18, 1924. Serial No. 733,470.

The object of this invention is to enable the drive wheels of a motor vehicle to obtain a positive grip upon a slippery surface, thereby preventing skidding and insuring a positive tractive action between the drive wheels and the surface of the road.

The invention provides an equipment including a container for sand or like abrasive material, means for supplying air under pressure to the container to effect a positive discharge of the sand therefrom, a delivery spout and a valve associated with said spout for controlling the discharge of the sand therethrough, said valve being under control of the driver.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is a detail view showing the application of the invention to an automobile,

Figure 2 is a detail view of the sand container and valved spout associated therewith, parts of the container being broken away,

Figure 3 is a top plan view of the parts illustrated in Figure 2,

Figure 4 is a diagrammatic view of the motor circuit,

Figure 5 is a detail view of a portion of the instrument board provided with the air gauge and motor circuit switch, and,

Figure 6 is a detail view of a valve control.

Corresponding and like parts are referred to in the following description and designated in the several views of the drawings by like reference characters.

The automobile illustrated in Figure 1 is typical of the type of motor driven vehicles for which the invention is designed, the same being shown to illustrate the application of the invention. The numeral 10 denotes a container which is of the form of a box for holding a quantity of sand or like

abrasive material, and this container may be of any construction and capacity and located upon the vehicle in the most advantageous position. A spout 11 extends from the container 10 and its delivery end is arranged to discharge sand upon the surface in advance of the driving wheel 12 of the vehicle, whereby to prevent slipping when negotiating a slippery surface. A valve 13 in the length of the spout 11 controls the discharge of the sand, and is normally held closed by means of a spring 14 and is adapted to be opened by means of a connection 15 which may be attached to a pedal 16 or a pull 17 within convenient reach of the driver, so that sand may be supplied to a slippery surface when operating the pedal 16 or by pulling upon the part 17.

The numeral 18 denotes an electric motor and 19 an air compressor adapted to be operated by means of the motor 18, a pipe 20 connecting the air compressor with the box or container 10, to supply air thereto under pressure. A check valve 21 is located in the length of the air pipe 20 to prevent loss of pressure when the air compressor is at rest. A gauge 22 disposed upon the instrument board or in any other preferred location is connected by means of a pipe 23 with the sand box or container 10, so that the driver may ascertain at a glance the pressure of the air within the container 10. A screen 24 arranged over the end of the pipe 23 connected to the box 10 prevents sand from entering said pipe and impairing the action of the gauge 22. A switch 24 mounted upon the instrument board is included in the circuit containing the motor 18 and when the switch 24 is closed current is supplied to the motor 18 whereby the air compressor 19 is operated to supply the box or container 10 with air under pressure.

In the operation of the invention, sand may be supplied to a wet or slippery surface to prevent slipping and enable the drive wheels of a motor vehicle to obtain a positive grip and the sand is discharged either upon operating the pedal 16 or by pulling upon the part 17.

As indicated most clearly in Figure 1, a box 26 or like receptacle may be located beneath a seat of the vehicle and receive a quantity of sand which may be supplied to

the surface by gravity through a spout 27 leading therefrom, the discharge of the fan being controllable in any preferred way.

What is claimed is:—

- 5 A sanding unit attachment for disposition on a motor vehicle, the attachment comprising a sand box, a discharge pipe leading therefrom, a valve operable to control the discharge through said pipe, means to operate said valve accessible by the vehicle driver

while seated, an air compressor in communication with the box, and a motor independent of the motor of the vehicle to operate said air compressor and a control means for the motor accessible to the vehicle driver while seated. 15

In testimony whereof I affix my signature.

ARTHUR W. REED.
